UNITED STATES PATENT OFFICE

2,566,581

STEREOTYPE CASTING MACHINE

Wayne Peterson, Moorhead, Minn.

Continuation of application Serial No. 14,262,
 March 11, 1948. This application April 28, 1950,
 Serial No. 158,747

1 Claim. (Cl. 22—3)

1

My invention relates generally to stereotype casting machines, and, more specifically, to a stereotype casting machine scorcher combination. The present application is a continuation of application Serial No. 14,262, filed March 11, 1948, now abandoned.

The primary object of my invention is the provision of a novel arrangement, including casting platens, metal pot, heater, and scorcher, wherein the heat utilized to melt type metal in the metal pot is also utilized for heating the scorcher platen.

Another object of my invention is the provision of a novel scorcher having relatively fixed and movable platens which may be readily separated for the insertion and removal therebetween of matrix to be dried and which will quickly close under the action of gravity without exerting undue (but uniform) pressure upon the matrix.

A still further object of my invention is the provision of a novel construction, which is rugged in construction, easy and quick to operate, and inexpensive to maintain.

The above and still further objects of my invention will become apparent from the following detailed specification, appended claim, and attached drawings.

Referring to the drawings, wherein like characters indicate like parts throughout the several views:

Fig. 1 is a perspective view of a stereotype casting machine incorporating my novel scorcher;

Fig. 2 is a side elevation with some parts being broken away and some parts shown in section;

Fig. 3 is an enlarged fragmentary view in cross section, taken substantially on the line 3—3 of Fig. 1; and

Fig. 4 is a view corresponding to Fig. 3, but showing a different position of some of the parts.

Referring with greater particularity to the drawings, the numeral 1 indicates, in its entirety, a frame structure preferably comprising laterally-spaced substantially parallel side members 2, a rear member 3, and a front member 4. The frame 1 is adapted to support, for rocking movements intermediate the side portions 2, a casting box having a lower platen 5 and an upper platen 6, which may be mounted therein in any conventional manner, such as illustrated in my Patent No. 2,442,246. Projecting upwardly from the frame 1, adjacent the front end 4 thereof, are a pair of laterally-spaced parallel supporting members in the nature of flanges 7. Located intermediate the flanges 7, adjacent the upper portion thereof, and pivotally mounted thereto (as indi-

2

cated at 8) is an elongated metal box or melting pot 9, which has upwardly-diverging sides 10. A tilting lever 11 is secured fast to the metal box 9 through one of the pivot connections 8 for tilting the metal pot 9 when it is desired to pour through a suitable pouring spout 12 formed in the rear wall 10 thereof. It will be observed that the pivot connections 8 are located to one side of the longitudinal center of the metal box 9. A front wall 10 of the metal box is provided with a forwardly-projecting flange 13, which is adapted to normally rest upon a supporting bracket 14 connecting its opposite ends to forward edges of the upstanding flanges 7.

Heating means, such as a gas burner 15, is supported by the frame 1 through the medium of a pipe 16 and underlies the metal box 9 in spaced relation thereto. The numeral 17 indicates a suitable valve in the pipe or line 16.

A scorcher, generally used to dry the mats before placing the same between the casting platens 5 and 6, is mounted in a novel manner to utilize the waste heat from the heating element 15, deflected from the front side 10 of the metal pot 9, as shown. A relatively fixed scorcher platen 18 is secured intermediate the flanges 7, but forwardly thereof, by means of brackets 14 adjacent the upper edge of the flanges 7, and a pair of similar brackets 19 adjacent the lower ends of the flanges 7. It will further be observed that

platens 18 inclines slightly in a rearward direction and is provided preferably with a plurality of integrally-formed ribs 20 which serve not only to reinforce the same but also to provide heat-catching pockets. With reference particularly to Fig. 2, it will be observed that the bottom end of the scorcher element 18 projects below the level of the heating element 15, whereas the top edge thereof projects above the level of the metal box 9 with the rearwardly-inclined edge 21 thereof being in substantially the same vertical plane as the adjacent flange 13 of the metal box 9. It will further be observed, by reference to Fig. 2, that the heating element 15 is in a plane below

medial center of the scorcher element 18. With this novel arrangement, the heat emanating from the heating element 15 is impinged upon the bottom of the metal box 9, whereupon it is deflected laterally outwardly and into contact with the scorcher element 18. The rearward inclination of the platen 18 assures a maximum utilization of the heat rising upwardly therebetween and the forwardly-inclined side 10 of the metal box 9.

A movable platen 22 is mounted for movements toward and from face-to-face contact with the

fixed platen 18 by means of opposed pairs of diagonally-disposed links 23, pivotally connected at their opposite ends to the side edges of the platens 18 and 22. It will be noted that the links 23 are parallel to each other and that one thereof is extended to form an operating lever 24. With this arrangement, the movable platen 22 is gravity-biased toward contact with the fixed platen 18 and may be moved upwardly and outwardly therefrom by merely pulling downwardly on the operating lever 24, as indicated by dotted lines in Fig. 2. Referring particularly to Figs. 3 and 4, it will be seen that the inner adjacent faces of the platens are covered with suitable materials such as asbestos, indicated by the numeral 25. In use, the operating lever 24 is depressed to its dotted line position of Fig. 2, whereby to dispose the platens 18 and 22 in the spaced relation indicated in Fig. 4 and a mat inserted therebetween. Thereafter, the operating lever 24 is released and the movable platen 22 moves under the action of gravity toward contact with the fixed platen 18, as indicated in Fig. 3, whereby to frictionally hold the mat or matrix between the asbestos sheets 25 until it is dry. The matrix is indicated in Fig. 3 by the numeral 26. It will be noted that one matrix 26 may be drying between the scorching platens 18 and 22 while another thereof is being used in the casting box made up of the platens 5 and 6. The novel combination illustrated not 30

only saves time but also utilizes waste heat for the drying of the matrix.

What I claim is:

5 In a device of the class described, a pair of spaced vertically-disposed frame members, a metal pot secured intermediate said members adjacent their upper ends, a pot heating element immediately below said metal pot for heating the same, and a scorching plate carried by the upper portions of said frame members and shaped to extend therebetween and project above and laterally outwardly of said metal pot to provide therewith a heating zone for matrix to be dried.

15 WAYNE PETERSON.
